CLAIM

The ornamental design for a file and chisel handle, as shown and described.

DESCRIPTION

FIG. 1 is a front, left, top perspective of a file and chisel handle according to our new design.

FIG. 2 is a front, right, bottom perspective of the file and chisel handle thereof.

FIG. 3 is a front view of the file and chisel handle thereof.

FIG. 4 is a rear view of the file and chisel handle thereof.

FIG. 5 is a left-side view of the file and chisel handle thereof.

FIG. 6 is a right-side view of the file and chisel handle thereof.

FIG. 7 is a top view of the file and chisel handle thereof; and,

FIG. 8 is a bottom view of the file and chisel handle thereof.

The broken lines shown in the drawings are for the purpose of illustrating unclaimed portions of the file and chisel handle and form no part of the claimed design.

Notably, the combination of the bottom “H” design of the handle depicted in FIG. 8, and the handle ridges on the sides of the handle as well as the ridges for thumb gripping are novel design features of our invention.
